UNITED STATES PATENT OFFICE

137,464

DESIGN FOR A TAPE DISPENSER

Greydon W. Nedblake and Ray H. Nordeen, North
Kansas City, Mo.

Application October 25, 1943, Serial No. 111,494

Term of patent 3½ years

To all whom it may concern:

Be it known that we, Greydon W. Nedblake and Ray H. Nordeen, citizens of the United States, residing at Dundee Hills Addition and Green Haven Addition, respectively, North Kansas City, in the county of Clay and State of Missouri, have invented a new, original, and ornamental Design for a Tape Dispenser, of which the following is a specification, reference being had to the accompanying drawing, forming part thereof.

Fig. 1 is a perspective view of a tape dispenser showing our new design.

Fig. 2 is a side elevation of the tape dispenser.

Fig. 3 is a top plan view of the tape dispenser.

Fig. 4 is a front elevation of the tape dispenser.

We claim:

The ornamental design for a tape dispenser, as shown.

GREYDON W. NEDBLAKE.
RAY H. NORDEEN.
